BOTTLE CLOSURE DEVICE.

Application filed April 19, 1927, Serial No. 184,872, and in Austria April 23, 1926.

Our invention relates to cap closures for bottles and the like of the type comprising a disk of pulp board or paper or other suitable material, which is adapted to be forced 5 into the interior of the bottle neck to fit therein and to form an effective closure and it has for its object to provide a seal or closure of the kind mentioned which prevents repeated use of the disk and which when 10 once removed or damaged will not allow reinsertion or restoration in such a manner that the sealing of the bottle will have an uninjured appearance.

We intend to employ a seal or closure of 15 this kind especially in connection with milk bottles as it is of special importance when milk is supplied to town districts by means of a large number of bottles which have been sealed in the dairies to prevent persons 20 engaged in the distributing service or the retail dealers to open the same and to partly evacuate the bottles or to fill them partly with other material.

To attain the object of this invention the 25 seal or closure consists of a number of separate components which fit each other exactly, so as to form a circular composite disk when assembled. If it is tried to remove the seal or closure the several separate components 30 forming the circular composite disk will come apart and the seal or closure will be destroyed and cannot be restored by reassembling the components and reinserting them into the bottle. A number of cap closures for bottles have already been proposed 35 in which some part has been weakened so that the disk will break at this predetermined place or in which some part is cut out and covered by another material to allow 40 introduction of the finger tip in order to remove the disk. Caps of this kind do not however act as a safety device as they always can be removed from the margin and reinserted in such a manner that the uninjured 45 appearance is preserved and this can only be prevented by providing a special construction of the bottle neck, which must in this case hold down the disk by a locking ledge. The object of this invention is to 50 provide a cap acting as a safety device under all conditions and within bottles of various kinds with no specially formed neck, such

object being accomplished by providing not a uniform and coherent cap closure but a number of separate component disks of such 55 a shape as to fit snugly and to complete each other so as to form a complete sealing disk within the bottle neck, which can however not be withdrawn as a whole when once inserted. Preferably the separate component 60 disks are so shaped that the separating or dividing lines between the component disks run from the margin towards the center so that the margin is subdivided, thus eliminating every possibility of lifting the cap 65 closure from the margin by an appropriate tool without destroying the composite sealing disk, so that the components come apart.

A preferred form consists in a central disk with radially extended arms between which 70 the other components preferably of sector shape are to be inserted.

In order to allow convenient handling of the composite disks consisting of separate components and to prevent any reassembling 75 having the appearance of an uninjured seal and to allow sealing by the usual sealing machines the components may be superficially and slightly held in contact with each other by any appropriate means capable of 80 breaking under a very slight strain, such as a small layer of varnish applied to their surface or by glueing upon them a very thin sheet of light paper covering approximately 85 the surface of the composite disk, which layer or sheet must however offer such a small resistance that it will immediately be broken or torn and will allow the components to come apart when the closure device is tampered with.

90 Other features of our invention will appear from the following detailed description.

The invention is illustrated in the accompanying drawings, in which

95 Fig. 1 represents the improved cap when inserted into the neck of a bottle,

Fig. 2 represents a sectional view of the cap,

100 Fig. 3 is a plan view of the closure device, when covered with a layer holding the parts together,

Fig. 4 is another modification of the closure device.

As will be seen from Figs. 1-3 of the drawings the composite disk forming the seal or closure of the bottle 8 consists of several separate components, for instance of 5 a central part 1, having radially extending arms or ribs 2, and of sectors 3-6 completely filling the space between said ribs. The sectors 3-6 when inserted between the ribs will form together with the central body 10 a complete circular composite disk. To ensure breaking of the sectors even when only small holes are made in them transverse cuttings or slits 9 may be made which entirely cut through the sector material and only 15 leave a small strip of material uninjured. (Figs. 2 and 3.) To allow easier manipulation especially when inserting the disks into the bottle necks and to prevent reassembling of parts that have fallen apart it is prefer- 20 able to apply a layer of varnish on the surface of the disk. This will be sufficient to hold the disks together during the inserting operation which, as well known is made by a kind of reciprocating plunger or piston 25 having approximately the same diameter as the bottle neck, the disks being fed to said plunger, which on its downward movement carries them as a whole into the bottle neck where they are held together. As the 30 plunger acts on the whole surface of the disk, the parts will not fall apart during such operation if held against radial movement superficially.

Instead of employing a small layer of 35 varnish also a silk paper, tissue paper or cambric paper or another very thin sheet of paper may be glued upon the disks when assembled, which will cause sufficient adhesion of the parts in a radial direction to 40 allow insertion but which will break or will be torn as soon as it is tried to withdraw the seal from the bottle neck, or to apply any force upon the plane surface which will cause bending of the disk. Especially when 45 it is tried to remove the closure device the friction at the edges which must snugly fit into the bottle neck will cause bending or distortion of the disk which will immediately lead to destruction of the layer or sheet or 50 other binding means between the components and thus will also destroy the uninjured appearance of the disk.

We wish it to be understood that the way 55 in which the composite disk is divided into several components is not limited by the example given, as it is of course possible to use several forms which will equally well answer the requirements. A further example of the way in which the disk may be divided is 60 illustrated in Fig. 4 according to which the disk is divided into a series of concentric annular parts holding together at their periphery and which may be subdivided into 65 sections.

Preferably manufacturing of the disk takes place by cutting first a circular disk out of wood pulp board and by afterwards cutting through said disk entirely by means of cutters of the desired shape. It is thus 70 ensured that always the parts cut from the disk are fitting closely and snugly together.

In actual use the surface of the disk or the layer upon said surface will be provided with a mark or with any other sign or device from 75 which it is immediately seen whether the seal put upon the bottles in the dairy is uninjured. Prints upon the layer covering the disk will be sufficient for this purpose.

We do not limit ourselves to the examples 80 shown as many modifications are possible without departing from the essence of the invention.

What we claim is:

1. A bottle closure and safety device 85 against surreptitious use comprising a cap consisting of a number of separable components fitting snugly and exactly at their edges and shaped so as to form a complete composite closure disk when assembled. 90

2. A bottle closure device comprising a cap consisting of a number of separable components fitting snugly and exactly at their edges and shaped so as to form a complete composite closure disk when assembled, the 95 dividing cuts between said components running from the marginal edge in a substantially radial direction toward the center of the disk.

3. A bottle closure and safety device 100 against surreptitious use comprising a cap consisting of a number of separable components fitting snugly and exactly at their edges and shaped so as to form a complete composite closure disk when assembled, said components consisting of a central body cut so as to have a number of radial arms with the cuts running in a substantially radial direction from the marginal edge toward the center and a number of sector shaped components disposed to fill the spaces between 105 said arms. 110

4. A bottle closure device according to 115 claim 3 said sector shaped components being provided with slits directed towards their marginal edges.

5. A bottle closure device comprising a number of separable component disks exactly fitting each other so as to form a composite disk when assembled, means capable 120 of being attached to all components for holding the parts slightly together in a radial direction but adapted to be destroyed by any attempt to remove the closure from the bottle. 125

6. In a bottle closure and a safety device comprising a number of separable components exactly fitting each other so as to form a composite disk when assembled, a common 130

thin layer covering substantially all the components for holding the parts slightly together in a radial direction, but adapted to break at any attempt to remove the closure 5 from the bottle.

7. A bottle closure device according to claim 6, with a layer consisting of thin tissue

paper glued to all components and forming 10 a common cover for the component disk.

In testimony whereof, we have hereunto set our hands.
